UNITED STATES PATENT OFFICE

WILLIAM D. ANTRIM, OF GLOUCESTER, NEW JERSEY, ASSIGNOR TO ROBERTS & MANDER STOVE COMPANY, OF PHILADELPHIA, PENNSYLVANIA, A CORPORATION OF PENNSYLVANIA

SAFETY DEVICE FOR GAS STOVE MANIFOLDS

Application filed June 8, 1929. Serial No. 369,431.

My invention relates to certain improvements in the gas manifolds of gas ranges, in which the manifold is connected to the burners of the ranges by a series of gas cocks.

The object of the invention is to provide a safety device which will prevent the turning of a cock controlling the gas to an oven when the broiler cock is turned, or vice versa.

10 This object I attain in the following manner, reference being had to the accompanying drawings, in which:

Fig. 1 is a front elevation of a gas range illustrating my invention;

15 Fig. 2 is an enlarged front elevation of the gas cocks controlling the oven burner, and the broiler burner in the upper portion of the oven and illustrating the safety device;

Fig. 3 is a plan view of Fig. 1; and

20 Fig. 4 is a detached perspective view of the safety device.

The body 1 of the gas range is of any of the standard constructions having an oven 2. In the lower portion of the oven is an oven burner and in the upper portion of the oven is a broiler burner. At the top 3 of the oven in the present instance are four top open burners.

The manifold 4 extends across the front 30 of the gas range as shown in Fig. 1. Cocks 5 control the flow of gas from the manifold 4 to the several top burners, while the cock 6 controls the gas from the manifold to the broiler at the top of the oven and the cock 7 controls the flow of gas from the manifold to the oven burner in the lower portion of the burner.

In order to prevent gas from flowing into the oven from one burner when the gas from the other is ignited, means is provided which prevents the operation of one cock while the other cock is turned on.

The safety device can be readily clamped in position and can be moved into position 45 to prevent the movement of either cock.

A bracket 8 has sockets 9 which engage the underside of the pipes 10 and 11 leading from the cocks 6 and 7, respectively, and is secured thereto by a clamp plate 12 also having sockets to engage the pipes, and the clamp

plate is secured to the bracket by a bolt 13, so as to hold the bracket rigidly to the pipes. On the bracket is a lug 14 to which is pivoted at 15 to a lever 16 having an upright lug 17. A guard 18 is secured to the lug by a bolt 19. This guard extends under the cock 6 and has two arms 20 and 21 which are shaped so as to cover handles of the cocks 6 or 7 when in one position or the other.

When the guard is in the position shown in Figs. 2 and 3, the arm 20 is in position in front of the handle 6a of the cock 6, and the handle 7a of the cock 7 leading to the oven burner is free to be turned, and when it is turned the handle 7a prevents the guard 65 moving on its pivot, locking the cock 6 in its closed position. When both cocks are closed, the guard can be moved to uncover either cock, and when the cock 6 is turned its handle 6a prevents the guard being turned, locking the cock 7 in its closed position.

The back of the guard 18 has a transverse groove 22, in the present instance, in which fits the lug 17, and this lug is grooved to receive a nut 19a on the bolt 19. These details of construction may be modified without departing from the main features of the invention.

The arms 20 and 21 of the guard are of such shape and size that they can have the words "Oven" and "Broiler" cast thereon.

I claim:

1. The combination in a gas range, of an oven gas cock and a broiler gas cock arranged side by side and having handles, each handle being arranged for movement from a vertical to a horizontal position or vice versa; and a guard pivoted back of the handles and independent thereof and having arms in front of the handles of the gas cocks and spaced so that when the guard is turned in one position, one of its arms will cover the handle of one cock and the other arm will uncover the handle of the other cock so that it can be turned.

2. The combination in a gas range, of two handled gas cocks mounted at the front of the range; gas pipes extending from the gas cocks to the burners of the range; a bracket back of the gas cocks and having sockets

which partly encircle the pipes; a clamp plate attached to the bracket, securing the bracket to the pipes; a lever pivoted to the bracket and extending towards the front of the range; and a guard carried by the lever and having arms thereon which are located in front of the gas cocks, said arms being so proportioned that one arm will be located in front of the handle of one gas cock, while the other arm will be at one side of the handle of the other gas cock, so that its handle is free to be turned.

3. The combination in a gas range of an oven gas cock and a broiler gas cock spaced from each other and having handles for turning the same, a mounting, a guard comprising spaced plates each of substantially the area of each handle pivoted to said mounting and lying in a plane adjacent the front of the handles for contact therewith, the space between the plates being less than the space between the handles whereby one plate will substantially cover one of the handles and prevent turning thereof while the other handle is exposed for operation.

WILLIAM D. ANTRIM.
